(57) CLAIM

The ornamental design for a garment protector, as shown and described.

DESCRIPTION

FIG. 1 is a front elevational view of the garment protector of the present invention;

FIG. 2 is a rear elevational view of the garment protector of FIG. 1;

FIG. 3 is a right side elevational view of the garment protector of FIG. 1, the left view being a mirror image thereof;

FIG. 4 is a top plan view of the garment protector of FIG. 1; and,

FIG. 5 is a bottom plan view of the garment protector of FIG. 1.

The broken lines showing of a clothing pocket in FIGS. 1, 2, 3, 4, and 5 are for illustrative purposes only and form no part of the claimed design.

1 Claim, 2 Drawing Sheets

FIG. 4

FIG. 1

FIG. 3

FIG. 2

FIG. 5
